Des. 178,714
Patented Sept. 4, 1956

178,714

COMBINATION WINDOW AND ARCHWAY TRIM

Alvin A. Woodward, Ketchikan, Territory of Alaska

Application August 12, 1955, Serial No. 37,508

Term of patent 14 years

(Cl. D13—1)

Fig. 1.

Fig. 2.

Fig. 3.

FIG.4.

FIG.5.

FIG.6.

Figure 1 is a front elevation of a combination window and archway trim showing my new design,

Figure 2 is a top plan view thereof,

Figure 3 is a vertical section taken on line 3—3 of Figure 1,

Figure 4 is a rear elevation thereof,

Figure 5 is a horizontal section taken on line 5—5 of Figure 1 and,

Figure 6 is an end view of the device.

I claim:

The ornamental design for a combination window and archway trim, as shown.
